ACCESSORY

Aaron Landis, New York, N. Y.

Application April 24, 1934, Serial No. 722,124

12 Claims. (Cl. 41—34)

This invention relates to accessories for hand bags and the like articles, worn or carried by women.

An object of this invention is to provide a device of the character described, in the form of an accessory for a lady's hand bag, or other article, worn or carried by women, or forming part thereof, and having means adapted to be arranged to expose different colors or different combinations of colors, whereby the article may be used with differently colored ensembles.

Another object of this invention is to provide an improved device of the character described, incorporated into or forming an ornament for a lady's hand bag.

Still another object of this invention is to provide a hand bag or other article, worn or carried by women, having an exterior, or portion of the exterior thereof, in the form of a removable colored member which may be replaced by another differently colored member, whereby said hand bag or article may be carried with differently colored ensembles.

Still another object of this invention is to provide a lady's vanity case provided with a top cover having an opening exposing a portion of a colored plate, the construction permitting the plate to be rotated to expose differently colored portions thereof.

Still another object of this invention is to provide a compact, neat and attractive construction of the character described, which shall be comparatively inexpensive to manufacture, comprise few and simple parts, be easy to manipulate, or adjust, and which shall yet be practical and efficient to a high degree.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which is shown one of the various possible embodiments of this invention,

Fig. 1 is a perspective view of a lady's hand bag provided with a device embodying the invention;

Fig. 2 is a cross-sectional view taken on line 2—2 of Fig. 1;

Fig. 3 is an enlarged perspective view of a portion of the bag shown in Fig. 1, showing one of the colored plates being partly removed;

Fig. 4 is a still further enlarged, perspective view of portions of the colored plates;

Fig. 5 is a partial, front, elevational view of a lady's hand bag embodying the invention and illustrating a modified construction, parts being broken away;

Fig. 6 is a cross-sectional view taken on line 6—6 of Fig. 5 through the opening ornament;

Fig. 7 is a view similar to Fig. 5 with parts broken away to show the interior construction;

Fig. 8 is a cross-sectional view of the opening ornament shown in Fig. 7 in lifted position;

Fig. 9 is a view similar to Fig. 7, but illustrating a still further modified construction, parts being broken away;

Fig. 10 is a cross-sectional view taken on line 10—10 of the opening ornament shown in Fig. 9;

Fig. 11 is a front elevational view of an opening ornament of a hand bag, illustrating another modified construction;

Fig. 12 is a cross-sectional view taken on line 12—12 of Fig. 11;

Fig. 13 is a cross-sectional view taken on line 13—13 of Fig. 11;

Fig. 14 is a view similar to Fig. 11 and illustrating yet another modification;

Fig. 15 is a cross-sectional view taken on line 15—15 of Fig. 14;

Fig. 16 is a cross-sectional view taken on line 16—16 of Fig. 14;

Fig. 17 is a front elevational view of a portion of a lady's hand bag provided with a device embodying the invention and illustrating still another modified construction thereof, parts being broken away;

Fig. 18 is a cross-sectional view taken on line 18—18 of Fig. 17;

Fig. 19 is a perspective view of a lady's hand bag embodying the invention and illustrating a still further modification thereof;

Fig. 20 is an enlarged cross-sectional view taken on line 20—20 of Fig. 19, parts being broken away;

Fig. 21 is a top plan view of an opening ornament for a lady's hand bag in the form of a vanity case, embodying the invention and illustrating a still further modification thereof;

Fig. 22 is a cross-sectional view taken on line 22—22 of Fig. 21; and

Fig. 23 is a top plan view of the colored plate in the device shown in Fig. 21.

Referring now in detail to the drawings, 10 designates a lady's hand bag embodying the invention and comprising a body 11 having a flap 12 folded over the top of the front portion 14 there-

of. Fixed to said front portion is a square shaped block 16, and pivotally mounted on said block 16 by an axial rivet 18 is a knob 17 of the same shape. Thus the knob 17 registers with the block 16, but 5 may be rotated to the position shown in Fig. 1 in which the corners of said knob project beyond the sides of said block. Fixed to the flap 12 is a member 20 provided with a pair of spaced, projecting ears 22. Pivoted to said ears and disposed therebetween is a U-shaped frame 24 having side and bottom portions formed with grooves or channels 25.

Slidably received within the channels 25 are a plurality of differently colored, similarly shaped, 15 interchangeable plates 27, 28 and 29. Said plates are provided with registering, square, central openings adapted to receive therethrough the aligned block 16 and knob 17. Said plates may be inserted into the channels by moving the flap 20 to the position shown in Fig. 3 with the frame 24 disposed at an angle to the flap, in which position the top of the frame is open.

The plates may thus be removed or inserted through the top of the frame when the latter is 25 in the angular position shown in Fig. 3. However, when the member 24 is moved into the plane of the flap 12, the member 20 serves to close the top of the frame to prevent the plates from accidentally falling out.

30 The frame 24 with the plates inserted therein is held in position for closing the bag by the knob 17, as shown in Fig. 1, with the corners of the knob extending beyond the sides of the block 16 and contacting said plates. The bag may be 35 opened by merely turning the knob 17 into registration with the block 16 to permit the frame 24 to be moved away from the body of the bag. The plates 27, 28 and 29 may be interchanged to expose different colors, so that the bag may be 40 carried with differently colored ensembles. Said plates may be formed with non-registering openings 30 to expose different combinations of colors. Where openings 30 in the plates over-lap, a combination of more than two colors is exposed.

45 In Figs. 5 and 6 there is shown a modified form of the invention in the form of a bag 10a having hinged frame portions 32 and 33. Fixed to the frame portion 32 is a curved member 34 and fixed to the frame portion 33 is a hinge 35 adapted 50 to snap beneath the member 34. Hinged onto the hinge 35 is a metal strip 36 to which is attached an ornament 37 adapted to open the bag upon swinging the ornament upwardly. The ornament 37 comprises a member 38 open at the rear to form a chamber 39 and having a front wall 40 formed with a central square opening 41 and with a curved cut out portion or opening 42. Received within the chamber 39 is a disc 44 to 55 which there is fixed a square block 45 adapted to pass through the square opening 41.

60 Pivoted to the block 45 is a knob 46 of the same shape as said block and rotatable about the axis thereof on rivet 46a. Disposed within the chamber 39 and between the disc 44 and the front wall 40, are a plurality of similarly shaped, differently colored plates 47 having registering square shaped openings 48 receiving the block 45 and knob 46 therethrough. The plate adjacent the front wall 40 is partly exposed through opening 42 and by interchanging the plates, different colors may be exposed.

65 As shown in Fig. 6, the block 45 passes through the openings 48 in the plates 47 and through the opening 41 in the front wall 40. The knob 46 is turned out of registry with the block 45

engaging the front surface of the front wall 40 for retaining the disc 44 and the plates 47 within the chamber 39. For replacing or changing the colored discs 47 the knob 46 may be rotated into registry with the knob 45 to permit the disc 44 to be removed. The colored plates 47 may then be interchanged and the knob 46 again passed through the opening 41 and then turned out of registry with respect to the block 45.

70 In Figs. 7 and 8 there is shown an ornament 37a 10 for a hand bag 10b adapted to open the bag in the same manner as ornament 37 opens bag 10a. The handle 37a comprises a member 50 open at the rear to form a chamber 51 and providing a front wall 52 formed with a segmental opening 53. 15 Rotatably mounted on the wall 52 by an axial rivet 54 is a circular disc 55 received within the chamber 51. Adhered to the inner surface of the disc 55 are a plurality of segments 56, 57, 58 and 59 each of a different color and together substantially covering said disc.

20 As shown in Fig. 7, the segment 58 is exposed. If it is desired to expose a different color, the disc 55 is rotated to any desired position to expose either one color or two colors. The bag 10b 25 may then be carried with differently colored ensembles, it merely being necessary to rotate the disc 55 to a position for exposing the proper colors to match the ensemble.

25 In Figs. 9 and 10 there is shown a hand bag 10c 30 provided with a pivoted ornament 37b illustrating a still further modified construction. The ornament 37b comprises a frame member 60 which may be of triangular or other shape and having a central opening 61 and provided with inwardly 35 extending flanges 62 at the front thereof forming a chamber at the rear. For the purpose herein-after appearing, there is pivoted to the front surface of the frame a hook 63. Received within the rear chamber is a disc 64 provided with an apertured ear 65 fixed thereto. The hook 63 is adapted to engage within the opening 66 of the ear 65 for retaining the disc 64 in the chamber. Interposed between the disc 64 and the flange portion 62 are a plurality of differently colored plates 68, 45 formed with registering slots for receiving the ear 65. The plates 68 may be of different colors and are interchangeable to expose a suitable color. The discs 68 may be interchanged by releasing the hook 63 to permit removal of the disc 64.

50 In Figs. 11, 12 and 13 there is illustrated a hand bag ornament 37c illustrating a still further modified construction. The ornament 37c comprises an elongated block or member 70, the front surface whereof is depressed as at 71. The block 55 70 is furthermore formed with a pair of inwardly turned, parallel guide flanges 72 forming a pair of grooves 73. Slidably mounted on the depressed surface 71 are a plurality of colored plates or strips 75, the edges whereof are received within 60 the grooves 73. The strips 75 are formed with registering central openings 76 and the block 70 is formed with a central, screw threaded opening 77. Screwed within said opening 77 is a knob 78 having a screw threaded shank 79 extending 65 through the registering openings 76, and being screwed within the opening 77. The member 78 prevents the strips from sliding off the block.

70 It will now be understood that the strips 75 may be removed or replaced by first unscrewing the knob 78. Said strips 75 may be of different colors and provided with openings 80 whereby more than one color may be exposed at one time.

75 In Figs. 14, 15 and 16 there is shown a hand bag ornament 37d comprising a block 82 pro-

vided with a square shaped projection 84, and a pair of spaced lugs 85. Mounted on the block 82 are a plurality of superimposed, similarly shaped, differently colored strips or plates 86 each having a square shaped opening 87 receiving the projection 84 therethrough and openings 88 receiving the lugs 85 therethrough.

Pivoted to the square projection 84 by rivet 89, is a square shaped knob 90 coaxial therewith. The knob 90 may be rotated to a position shown in Fig. 14 out of registry with respect to the square projection 84, to engage the strips 86 and retain the same on the block.

In Figs. 17 and 18 there is shown a front portion 14a of a lady's hand bag. Attached to the front surface of said portion 14a are a pair of parallel, symmetrically disposed guide members 91 having therebetween a plurality of similarly shaped, differently colored plates or strips 92. The strips 92 are removable and interchangeable to expose different colors, whereby the bag may be worn with different ensembles.

In Fig. 19 there is shown a lady's hand bag 100, to the sides of which there are fixed flexible guide strips 101 having inwardly extending flanges 102 forming grooves 103. Received between the guide flanges is a flat sheet 104 having the edges 105 thereof engage within the grooves 103. The sheet 104 may be flexible and of any suitable color, and may be removed by merely pulling the same out from between the flanges 102, whereby a sheet of a different color may be substituted.

In Figs. 21, 22 and 23 there is shown a lock-ornament 37d for a lady's hand bag in the form of a vanity case. The vanity case comprises a casing portion 110 adapted to receive a powder compact 111 and a puff 112. Pivoted to the casing 110, as at 114, is a cover 115 comprising a circular disc 116 to which there is pivoted by rivet 117, a second superimposed circular disc 118. The disc 118 is formed with a segmental opening 119. Received between the discs 116 and 118 and fixed to the inner surface of the disc 116 is a plate 121 formed with a central opening 122 receiving the rivet 117 therethrough. The plate 121 is divided into differently colored segmental portions 124. Either one of the portions 124 or parts of adjacent portions 124 are adapted to be exposed through the opening 119 by rotating the disc 118.

It will thus be seen that there is provided a device in which the several objects of this invention are achieved, and which is well adapted to meet the conditions of practical use.

As various possible embodiments might be made of the above invention, and as various changes might be made in the embodiments set forth, it is to be understood that all matter herein set forth or shown in the accompanying drawings is to be interpreted as illustrative and not in a limiting sense.

Having thus described my invention, I claim as new and desire to secure by Letters Patent:

1. In a lady's hand bag, guide means, a colored plate slidably received between said guide means and being removable and replaceable by another colored plate, and pivoted means for releasably retaining said plate between said guide means.

2. A lady's hand bag comprising a member pivoted thereto, a plurality of superimposed differently colored, interchangeable plates mounted on said member, said plates being provided with registering openings, a block extending through said openings, and a member regis-

tering with said block pivoted thereto and movable out of registry with respect to said block.

3. In combination, a member, a plurality of superimposed, similarly shaped, differently colored, interchangeable plates mounted on said member, said plates having registering openings, a member extending through said openings, and means cooperating with said member for clamping said plates together.

4. In a hand bag, a portion having a block fixed thereto, a knob rotatably mounted on said block, a plurality of colored plates having registering openings receiving said block therethrough and said knob being rotatable to engage said plates for retaining the same on said block.

5. In a hand bag, a portion having a block fixed thereto, a knob rotatably mounted on said block, a plurality of colored plates having registering openings receiving said block therethrough and said knob being rotatable to engage said plates for retaining the same on said block, at least one of said discs having an opening to expose a portion of another plate through said opening.

6. A lady's hand bag comprising a body having a front portion and a flap foldable over the top of said front portion, a block fixed to said front portion, a knob pivoted to said block and registering therewith and movable out of registry with respect thereto, a frame member pivoted to the edge of said flap, a plurality of superimposed, differently colored plates mounted on said frame and having registering openings adapted to receive therethrough the registering knob and block, whereby said knob may be rotated to a position out of registry with respect to said block to engage said plates.

7. A lady's hand bag, an ornament member pivoted thereto and being formed with a chamber in the rear thereof providing a front wall, said front wall having an opening, a disc having a block fixed thereto and received within said chamber with said block extending into said opening, a knob pivoted to said block and movable to a position engaging said front wall, and a plurality of differently colored plates interposed between said disc and said front wall and having registering openings receiving said plates, and said front wall being formed with a second opening to expose a portion of the colored plate adjacent the front wall.

8. A lady's hand bag, an ornament pivoted thereto and being chambered at the rear thereof forming a front wall, said front wall being formed with an opening, and a disc received within said chamber and pivoted to said front wall, and having differently colored portions on the inner surface thereof, said disc being rotatable to expose different colors through said opening.

9. A lady's hand bag comprising a frame mounted thereon, a plurality of superposed interchangeable ornamental plates mounted in said frame, said plates having registering openings, and a member extending through said openings for releasably holding said plates in said frame.

10. The combination with a lady's hand bag, of an ornamental device mounted thereon and externally thereof, said device comprising a member having an open top and a front opening, and a plurality of superposed interchangeable ornamental plates removably mounted in said member, said plates being insertable and removable through the open top of said member, and the uppermost plate being visible through the

said front opening, said member being exposed to view and constituting a visible part of the bag ornament, and means separate from said open top for releasably retaining said plates within said member.

11. In a hand bag, an ornament hinged thereto and comprising a chamber having a front wall provided with an opening, and a plate mounted within said chamber and having differently colored portions, said plate being movable

within said chamber to expose different colors through said opening.

12. In a hand bag, an ornament hinged directly to the bag and movable with respect thereto and comprising a member having a front opening and a colored plate mounted in said member and carried thereby, said plate being visible through the opening in said member.

5

AARON LANDIS. 10
